UNITED STATES PATENT OFFICE.

CHARLES WEISS, OF NEW YORK, N. Y.

DESIGN FOR A SAUCER OR THE LIKE.

Application filed January 22, 1929. Serial No. 29,729. Term of patent 7 years.

To all whom it may concern:

Be it known that I, CHARLES WEISS, a citizen of the United States, and resident of the Borough of Manhattan, city, county, and State of New York, have invented a new, original and ornamental Design for a Saucer or the like, of which the following is a specification, reference being had to the accompanying drawing, forming part hereof in which—

Fig. 1 is a plan view and Fig. 2 a central sectional view of a saucer or similar article illustrating my new design.

I claim:

The ornamental design for a saucer or the like, as shown.

CHAS. WEISS.
